[57] ABSTRACT

A control device for the work feeding mechanism of a sewing machine in which any one of three separate linkages may selectively be coupled to the feed regulating means of the sewing machine. The three linkages, for manual feed control, pattern cam influence of work feed, and automatic group stitching such as buttonholing, while organized in a compact subassembly are distinct and individually tailored each to satisfy its own special requirements.

CONTROL DEVICE FOR THE WORK FEEDING MECHANISM OF A SEWING MACHINE

BACKGROUND OF THE INVENTION

When fabricating stitched buttonholes using a general purpose sewing machine, as distinguished from a special purpose machine designed only to sew buttonholes, it is necessary that the sewing machine work feeding mechanism be regulated in a predetermined sequence of settings to feed forwardly and then rearwardly for the production of the closed buttonhole-shaped tack. Along with such work feed mechanism control, the zig-zag mechanism of the sewing machine must also be changed in a sequence of settings to provide the desired appearance of the stitch group.

In those sewing machines having only manual control for the feeding mechanism, buttonholing units are known which require a switching means for rendering either the manual control or the buttonholing control unit effective to regulate the feed. The U.S. patent application Ser. No. 739,051, filed June 21, 1968, now abandoned, Blackwood et al. exemplifies this type of feed mechanism control for buttonholing.

In those sewing machines equipped with pattern cam control of the work feeding mechanism effective during ordinary zigzag stitching, it is known to provide a special pattern cam for control of the work feeding mechanism during the formation of buttonholes. The U.S. patent application Ser. No. 827,867, filed May 26, 1969, Marsh et al. now U.S. Pat. No. 3,585,876, exemplifies this type of feed mechanism control for buttonholing. Where pattern cam control of the work feed mechanism is provided, a switching means is required for selecting manual or pattern cam control of the feed mechanism.

An advantage of a buttonhole mechanism which makes use of a cam controlled feed mechanism, when such is included in the sewing machine, is the economy gained by use of the cam controlled feed mechanism for two purposes. A disadvantage of such arrangement is that the feed cam mechanism must then be designed and manufactured with capacity for satisfying both of the widely differing requirements of decorative stitch patterns and of buttonholes. In decorative stitch patterns the need is for rapid changes over a wide range of stitch lengths, while in buttonholing only very small stitch lengths are used and the need is for uniform stitch length in forward and reverse direction.

SUMMARY OF THE INVENTION

This invention provides a novel control arrangement for the work feeding mechanism of a sewing machine in which three different regulators for the stitch length and direction of feed may be selectively brought into operative relation to the work feeding mechanism. An operator influenced control such as a dial is provided which over a first range of positions connects a first regulator to the work feeding mechanism by which the stitch length and direction may be selected manually. Over a second range of positions of the control dial the work feeding mechanism is connected to a second regulator which is influenced by a pattern cam driven by the sewing machine so that continuous lines of decorative stitches may be formed in which the stitch lengths and directions vary in accordance with predetermined patterns. Over a third range of positions of the control dial a third regulator is connected to the work feeding mechanism for producing closed stitch tacks such as buttonholes. The third work feed mechanism regulator is influenced by a cam means which is distinct from the stitch pattern cams which cooperate with the second feed regulator and thus the buttonhole influencing cam mechanism may be tailored exclusively for performing this distinctive task.

In this invention, the operator influenced control having three ranges of position for selecting which one of the three work feeding mechanism regulators shall be effective, also serves within certain of the ranges to influence additional regulation of the work feed mechanism. Thus within the first range of positions, the stitch length is set manually by turning

the control dial and within the second range of positions, turning of the control dial influences the ratio of pattern cam movement to work feed movement.

With the above and additional objects and advantages in view as will hereinafter appear, this invention comprises the devices, combinations and arrangements of parts hereinafter described and illustrated in the accompanying drawings of a preferred embodiment in which:

5 FIG. 1 represents a front elevational view of the standard end portion of a sewing machine with the front escutcheon panel removed and portions of the machine frame broken away to expose the mechanism therein forming a part of this invention,

10 15 FIG. 2 is a vertical cross-sectional view taken substantially along line 2-2 of FIG. 1 and showing the operator influenced control dial for selectively controlling which one of the three regulators will be connected to the work feeding mechanism, but illustrating only two of the three regulators, i.e., the regulator for manual feed control and the regulator for pattern cam control of the feed,

20 25 FIG. 3 is an elevational view of the control dial shown in FIG. 2 but with the cam grooves in the exposed face eliminated so that the cam grooves in the hidden face which are shown in dashed lines will clearly be indicated,

30 FIG. 4 is a vertical cross-sectional view taken substantially along line 4-4 of FIG. 1,

35 FIG. 5 is a disassembled perspective view of the control dial and of those two work feed mechanism regulators which are illustrated in FIG. 2,

40 FIG. 6 is a cross-sectional view of the assembled parts taken substantially along line 6-6 of FIG. 5 and showing the pivot stud for the cam control feed drive linkage together with the balancing adjustment,

45 FIG. 7 is a vertical cross-sectional view taken substantially along line 7-7 of FIG. 1 and illustrating the buttonhole influencing cam mechanism and the regulator for controlling the work feeding mechanism during buttonholing operations,

50 FIG. 8 is an elevational view of the control dial of FIG. 3 but showing the cam grooves in the exposed face thereof,

55 FIG. 9 is a vertical cross-sectional view taken substantially along line 9-9 of FIG. 1 and illustrating the ratchet drive mechanism for the buttonhole influencing cam, and

60 FIG. 10 is a disassembled perspective view of the buttonhole influencing cam mechanism and of the regulator for controlling the work feeding mechanism during buttonholing.

Illustrated in FIG. 1 are sufficient portions of a sewing machine frame clearly to indicate to those skilled in the art the disposition and general arrangement of this invention. The sewing machine frame includes a work supporting bed 11, a standard 12 rising from the bed, and a bracket 13 extending from the standard in overhanging relation to the bed. As shown in FIG. 1, the front wall of the standard and bracket arm is formed with an opening 15 bordered by a projecting rim 16 in which an escutcheon plate (not shown) may be seated. The drawings show the escutcheon plate removed to expose the mechanism. A top cover 17 for the bracket arm and a hinged lid 18 thereon are shown in cross section in FIG. 1.

65 70 A main shaft 20 is journaled in the bracket arm and may be rotated by any conventional means such as an electric motor or the like (not shown) to drive all of the mechanisms of the sewing machine. In the bracket arm, the main shaft may be provided with connections for operating a needle reciprocating mechanism and for driving pattern cams for influencing zigzag stitching and for providing cam control of the sewing machine work feed; these mechanisms may be of any known form, and therefore, are not illustrated in detail in the accompanying drawings.

75 76 A bed shaft 21 journaled beneath the work supporting bed 11 carries a sprocket 22 engaged by a timing belt 23 which is driven by a sprocket 24 on the main shaft 20. The bed shaft may be provided with connections for driving a loop taker and with connections for driving a work feeding mechanism and

since the loop taker, work feeding mechanism, and the drives thereto may be of any conventional form they are not illustrated in the accompanying drawings. The buttonholing mechanism and work feed controls of this invention are shown in the accompanying drawings in a form which is particularly suitable for use with a sewing machine as illustrated in the above-referred U.S. Pat. No. 3,585,876, it being understood that the buttonholing mechanism of this invention takes the place of the buttonholing mechanism of the aforementioned United States patent. Similarly, the present invention is particularly suitable for use with a sewing machine having a work feeding mechanism of the type of which only portions are shown in U.S. Pat. No. 3,585,876, and this work feed mechanism is described in greater detail in the copending U.S. application Ser. No. 810,951 filed Feb. 25, 1969, Szostak et al., now U.S. Pat. No. 3,593,769, to which reference may be had.

The work feeding mechanism with which this invention is particularly suitable for use includes a stitch length and direction regulating rock shaft 30 journaled in the sewing machine bed. One bushing, 31, for the feed regulating work shaft is shown in FIG. 1 seated in a web 32 of the sewing machine bed. A bracket 33 is made fast on the feed regulating rock shaft as by a setscrew 34 and this bracket is provided with means for accommodating engagement with any one of three separate linkages for regulating the sewing machine feed mechanism. The bracket 33 is formed with a depending rock arm 35 having a chamfered extremity 36 adapted to receive pattern cam influenced impulses to regulate the feed. The bracket is also formed with a lateral rock arm 37 which is drilled and tapped as at 38 to accommodate a fastening screw 39 on which is carried an eccentric collar 40 having a hexagonal flange 41. The eccentric collar is adapted to cooperate with a manual feed regulating linkage. At the free extremity of the lateral rock arm 37, a shouldered pin 42 is fastened in place, which pin cooperates with a linkage forming a part of the buttonhole mechanism as will be described hereinbelow. The bracket 33 is also formed with a projection 43 to which a spring 44 is attached. The spring is anchored in suitable manner on the sewing machine frame and serves to bias the feed regulating rock shaft 30 in a counterclockwise direction as viewed in FIG. 2 so as to urge the sewing machine work feeding mechanism toward an extreme position in the reverse direction of feed of the work fabric.

Referring to FIGS. 2 through 6, the general features of the mechanism of this invention will now be described with particular emphasis upon the mechanism for effecting manual control of the sewing machine work feeding mechanism. A "U"-shaped frame 50 is provided in which the mechanism of this invention is largely subassembled. The "U"-shaped frame 50 includes side limbs 51 and 52 and a base portion 53 joining the limbs. Mounting tabs 54 and 55, which extend outwardly from the side limbs 51 and 52 respectively, accommodate fastening screws 56 by which "U"-shaped frame is secured to mounting bosses 57 and 58 formed within the standard portion 12 of the sewing machine frame. As illustrated in FIGS. 1 and 5, an idler roller 59 for the bed shaft driving belt 23 may be carried by the side limb 51 of the "U"-shaped frame 50. The "U"-shaped frame 50 is also provided with an auxiliary "U"-shaped bracket 60 having side limbs 61 and 62 and a base portion 63 which is secured to the base portion 53 of the "U"-shaped frame 50 by screws 64. It will be appreciated that the above-described separate construction of the "U"-shaped frame and auxiliary bracket is suitable for sheet metal construction of these parts but that an integral frame member formed by molding or the like would be equally suitable.

Journaled between the side limbs 51 and 52 of the "U"-shaped frame 50 is a stud shaft 70 which at its right-hand extremity is sustained in the side limb 52 of the frame by a shouldered screw 71, while at the left-hand extremity the stud shaft is journaled in a flanged bushing 72 which bushing is held on the frame side limb 51 by a shouldered screw 74 serving to sustain the stud shaft and the flanged bushing in place. This

flanged bushing construction serves to provide a pivotal mount for an element of the buttonhole mechanism drive which will be described later in this specification.

5 Freely pivoted on the stud shaft 70 between the ends thereof is a quick reversing lever 75 for the sewing machine work feeding mechanism. The quick reversing lever is formed with a finger grip 76 at one extremity and is formed at the other extremity with a laterally offset tang 77 to which is attached a coil spring 78 anchored on a tab 79 struck out from the base portion 53 of the "U"-shaped frame 50.

10 To the right of the quick reversing lever 75 on the stud shaft 70, as viewed in FIGS. 1 and 5, is freely journaled a cam member 90. Spring clips 91, which are set into annular grooves 92 in the stud shaft 70, constrain the cam member 70 axially along the stud shaft. Preferably, the cam member is formed with a metallic hub 93 on which is molded the outer portion of the cam member which may be made of a synthetic plastic or the like. The cam member is preferably formed with 15 a fluted peripheral flange 94 for operator engagement to turn the cam member. On the right-hand face, as viewed in FIGS. 1 and 5, the cam member is formed with a spiral cam groove 95 shown in FIG. 8. Other recesses 96 in the right-hand face of the cam member serve only to reduce the mass of the cam member.

20 The left-hand face of the cam member 90 is formed with a cam groove 97 which, as illustrated in FIG. 3, includes three different portions. At one extremity a portion 98 of the cam groove 97 is provided for regulating manually the stitch length 25 of the work feeding mechanism and to this end the cam groove portion 98 is formed with sidewalls 99 and 100 which gradually diverge. Adjoining the manual feed regulating portion 98 of the cam groove is a second portion 101 of the cam groove which serves for positioning the parts for buttonholing operations; this portion 101 takes the form of a radially outwardly bowed segment of the cam groove 97. At the extremity of the cam groove 97 is formed the third portion 102 which also extends radially outward and serves to position the parts for pattern cam control of the work feeding mechanism.

30 Referring now to FIGS. 2, 5, and 6, a stud shaft 110 is carried between the side limbs 61 and 62 of the frame bracket 60. A spring clip 111 attached to the stud shaft 110 outside the side limb 61 of the bracket is formed with a projecting spring arm 112 which bears against the side limb 61 frictionally to resist turning movement of the stud shaft. At the other extremity, the stud shaft 110 protrudes through the side limb 62 of the bracket 60 and beyond the side limb 62 is fitted with a bushing 113 on which is pivotally mounted a cam follower lever 114 which is held on the bushing by a spring clip 115. At its free extremity, the cam follower lever 114 carries a laterally extending cam follower pin 116 which tracks the cam groove 97 in the left-hand face of the cam member 90 as viewed in FIGS. 1 and 5. The cam follower lever 114 is formed with a substantially radial slot 117 which accommodates the tang 77 on the quick reversing lever 75. Pivoted on a pin 118 on the cam follower lever 114 is a depending link 119 which is bifurcated as at 120 at the lower extremity to embrace the eccentric collar 40 which is secured on the lateral rock arm 37 of the work feed controlling rock shaft 30. A projection 121 extending from the depending link 119 is engaged by a spring 122 which is anchored on one extremity 123 of a wire keeper 124 which is attached by a screw 125 to the web 32 in the bed of the sewing machine. The other extremity 126 of the wire keeper 124 serves to constrain other parts of the sewing machine such as electrical wiring harness or the like away from interference with the mechanisms of this invention.

35 When the cam member 90 is turned to bring the cam follower 116 into the first portion 98 of the cam groove 97, the spring 122 will urge the cam follower against the inner sidewall 99 of the cam groove and as the dial is turned the cam follower will ride to varying distances from the center of the cam member shifting the depending link 119 which will regulate the angular position of the feed regulating rock shaft 30 accordingly. If at any time while the cam follower 116 is

tracking the diverging walled portion 98 of the cam track 97, the quick reversing lever 75 is depressed, the cam follower will be elevated to the extent permitted by the divergence of the outer wall 100 of the cam groove. The walls 99 and 100 of the cam groove are preferably constructed to dictate an approximately equal stitch length in reverse direction to the forward stitch length at any particular setting of the cam member 90. The coil spring 78 on the quick reversing lever 75 is desirable to prevent the quick reversing lever from rattling during operation of the machine.

FIGS. 2 and 5 illustrate in addition to the mechanism for manually regulating the work feeding mechanism, the mechanism whereby the work feed mechanism may be controlled automatically by a pattern cam to produce repetitive stitch patterns in which the work feed varies in a predetermined manner. In FIG. 2 a fragment of the pattern cam shaft 130 of the sewing machine is illustrated. This cam shaft is supported in the sewing machine bracket arm 13 and carries a worm wheel 131 in mesh with a worm (not shown) on the main shaft 20. A pattern cam 132 is illustrated on the pattern cam shaft 130 in a location usually consigned to control of the lateral position of the sewing machine needle and by which pattern cam controlled zigzag stitches are possible. Indicated generally at 133 atop the pattern cam shaft 130 is an exchangeable cam including a handle 134 which cam includes a pair of pattern cam flanges 135 and 136 of which the upper cam flange 135 is adapted to influence the work feeding mechanism by way of the linkage which will now be described.

Indicated at 139 in the drawings is a pattern cam follower lever adapted to track the cam flange portion 135. The cam follower 139 may be identical in construction and arrangement to the pattern cam follower for influencing the work feed mechanism in the U.S. Pat. No. 3,585,876, referred to hereinabove. The follower lever 139 is bifurcated at 140 and embraces a tang 141 on the upper extremity of a lever arm 142 and is formed at the opposite extremity with a slot 143 which embraces an eccentric portion 144 of a collar 145 which is secured to the stud shaft 110 as by a pin 146. A spring clip 147 may be provided between the cam follower lever 139 and the lever arm 142 to remove lost motion between these parts. Journaled on a concentric flange 148 formed on the collar 145 is a bellcrank lever 149 having an upstanding arm 150 which is bifurcated and embraces a pin 151 in the lever arm 142. The bellcrank lever also has a depending bellcrank arm 152 which at the lower extremity carries a pivot pin 153 for a link 154. A lateral pin 155 formed on the link 154 is selectively engageable with the depending rock arm 35 of the feed rock shaft bracket 32. Pivoted at 156 to the link 154 is a control strap 157 which at its upper extremity carries a cam follower pin 158 which extends into tracking relationship with the spiral cam groove 95 in the cam member 90. The cam follower pin 158 preferably projects through a slot 159 formed in a guard plate 160 which is located against the cam member 90 and which serves to conceal the cam grooves from the view of an operator of the sewing machine. The link 154 is preferably arranged in a guide slot 161 of a sheet metal bracket 162 which is secured as by screw 163 beneath the sewing machine standard.

As the cam member 90 is turned counterclockwise beyond the position illustrated in FIG. 2, the cam follower pin 158 in tracking the cam groove 95 will gradually raise the projection 155 on the link 154 upwardly into engagement with the depending rock arm 35. At the same time the cam follower 116 in tracking the third portion 102 of the cam groove 97 in the left-hand face of the cam member 90, as viewed in FIGS. 2 and 5, will first slightly depress the depending link 119 of the manual feed controlling linkage to move the depending rock arm 35 slightly in a clockwise direction as viewed in FIG. 2 to insure that the pin 155 will move into engagement with the right-hand side of the rock arm 35 as viewed in FIG. 2. The cam follower 116 in tracking the remainder of the cam portion 102 of the cam groove 97 will move the depending link upwardly to such an extent that the bifurcated end 120 of the

link will shift upwardly completely out of the range of possible contact with the eccentric collar 40, thus freeing the work feed regulating rock shaft 30 for influence solely by the pattern cam 135.

For balancing the pattern cam controlled influence of the work feeding mechanism so that the actual position of zero stitch length of feed motion may be regulated relatively to the pattern cam track, means are provided for shifting the angular relationship of the bellcrank lever 149 with respect to the lever arm 142. This balancing regulation is accomplished by means of a lever arm 170 which is fixed to the collar 145 on the stud shaft 110. A pivot pin 171 connects the lever arm 170 to a link 172 which extends upwardly and is pivotally connected in turn by a pin 173 to a crank arm 174 which is secured as by a clamp 175 to a dial segment 176. The dial segment 176 is journaled in a bearing aperture 177 formed in an upstanding arm 178 of a bracket 179 which is secured by screws 180 to the machine frame. The bracket arm 178 of the bracket 179 may be formed with an out-turned tang 181 for cooperation adjacent the periphery of the dial segment 176 to provide an indication of the balance setting of this mechanism.

Pivoted mounted in another bearing aperture 185 in the upstanding bracket arm 178 is a dial segment 186 formed with a radial finger grip tab 187 and with a projecting nose 188 arranged for engagement with the lever arm 142. The dial segment 186 when turned in a clockwise direction as viewed in FIG. 5, serves to shift the cam follower lever 139 so as to remove the cam follower from tracking relation with the pattern cam. This cam follower removal provision is useful when it is desired to exchange pattern cams. A pin 189 projecting from the dial segment 186 accommodates one extremity of a coil spring 190 of which the other extremity is anchored in the sewing machine frame so as to bias the dial segment 186 into a retracted inoperative position.

Referring now to FIGS. 7 to 10, the mechanism will be described by which a closed tack of stitches, such as a button-hole, may be made automatically with this invention. In FIG. 10 is illustrated a cam member 200 which regulates the automatic formation of buttonholes by the sewing machine and which is freely rotatable on the stud shaft 70 on the left-hand side of the quick reversing lever 75. The cam member 200 may preferably be constructed with a metallic hub portion 201 and with a molded plastic outer portion 202 enveloping the hub portion. The cam member 200 is formed with a peripheral flange 203 which is serated for better grip by a sewing machine operator, and as shown in FIG. 10 the cam member is formed in the right-hand face with a wide cam track 205 of which only the radially innermost wall 206 provides the active cam surface. Tracking the inner wall 206 of the cam track 205 is a follower pin 207 secured to one arm 208 of a three-armed lever 209 which is fulcrumed on a shouldered pin 210 secured in a tab 211 formed on the auxiliary bracket 60 in which the feed control unit is subassembled. An upstanding and forwardly extending lever arm 212 of the three-armed lever 209 has fixed at its free extremity a collar 213 formed with a bore 214 and provided with a setscrew 215 which can be threaded into the bore. A pivot pin 216 formed with an eccentric shoulder 217 and with a hexagonal head 218 is accommodated in the collar bore 214 and with the use of the setscrew 215 the angular position of the eccentric shoulder may be selectively determined. A depending link 219 is journaled on the eccentric shoulder 217 and the lower extremity of the depending link 219 is formed with a lateral abutment surface 220 and with a guide finger 221 depending beneath the abutment surface 220 and extending adjacent the shouldered pin 42 which is fixed in the rock arm 37 of the bracket 33 on the feed controlling rock shaft 30. A coil spring 225 is attached at one extremity to the depending arm 208 of the three-armed lever 209 and is secured at the other extremity to a fastening aperture 226 along the depending link 219 so as to bias the lateral abutment surface 220 of the link 219 toward a position as shown in FIG. 7 in engagement with the shouldered pin 42. A bellcrank lever 230 fulcrumed on a shouldered screw 231

threaded into the side limb 52 of the frame 50, is formed with a depending arm 232 carrying a lateral pin 233 which extends alongside the depending link 219, an upper arm 234 of the bellcrank 230 carries a cam follower pin 235 which extends through an aperture 236 in the guard plate 160 and tracks a cam groove 237 formed in the right-hand face of the cam member 90. As shown in FIG. 8, the cam groove 237 may be formed radially inwardly of the spiral cam groove 95 in the right-hand face of the cam member 90. The cam member 90, therefore, determines which of the three linkages will be operatively connected to regulate the work feed mechanism controlling rock shaft 30. As previously described, the cam member 90 moves the lever 119 into position for manual control of the work feeding mechanism during one range of position of the cam member 90, and in another range of positions influences connection of the link 154 with the work feed controlling rock shaft 30. As described immediately above, in a third range of positions of the cam member 90, the cam follower pin 235 will be urged radially outward into the position as illustrated in FIG. 8 so as to turn the bellcrank 230 thereof counterclockwise as viewed in FIG. 7, moving the lateral pin 233 to the right and allowing the coil spring 225 to draw the abutment 220 into engagement with the pin 42 on the rock arm 37. When the cam member 90 is in the position illustrated in FIG. 8, the manual feed controlling link 119 will be elevated by the cam groove portion 101 of the cam groove 97 and will be out of engagement with the work feed controlling mechanism. Similarly, when the buttonholing control link 219 is in effective feed regulating position as shown in FIG. 7, the pattern cam controlling linkage will be dropped out of effective position as shown in FIG. 2 by the spiral cam groove 95.

A tab 240 struck out from the upper arm 234 of the bellcrank 230 provides for attachment of a coil spring 241 anchored at the other extremity in a finger 242 formed on a spring clip 243 which is secured by screw 244 to the right side limb 52 of the frame 50. A bent finger 245 of the spring clip 243 projects through an opening 246 in the frame 50 and bears against the right-hand side face of the cam member 90 to provide a frictional resistance to the turning movement of the cam member 90 and to deter accidental angular shift of this cam member.

In the position of parts as shown in the drawings, therefore, in which the abutment 220 on the depending link 219 of the buttonholing mechanism is shifted into engagement with the pin 42, the follower pin 207 of the three-armed lever 209 in tracking the inner cam wheel 206 on the cam member 200 will influence the work feed mechanism of the sewing machine. The cam surface 206 is preferably formed so as to provide for a reversal of the feed direction upon movement of the cam member 200 in each quadrant of a complete turn of the cam member 200. In order to produce a buttonhole, only two changes of feed control are necessary, and therefore, a buttonhole may be produced with only one-half revolution of the cam member 200 or conversely, two buttonholes may be produced during one complete revolution of the cam member 200. The cam wheel 206 is preferably designed so as to provide movement of the three-armed lever 209 sufficient to influence only a very short stitch length of the work feeding mechanism in each direction of work travel through the machine. The eccentric shoulder 217 on the pivot pin for the depending link 219 is preferably formed with a very slight eccentricity so that a very accurate adjustment of the balancing between the forward and the reverse direction of work feeding can be attained. This very accurate stitch balancing ability of the present invention during buttonholing is advantageous because very slight differences in stitch length are readily apparent in a buttonhole because the opposite sides are stitched closely adjacent each other and the comparison is evident.

A third arm 250 is formed on the three-armed lever 209 and extends rearwardly and upwardly as shown in the drawings and carries a pivot pin 251 which engages a slot 252 formed in a crank arm 253 fast on a rock shaft 254 which is journaled in spaced upstanding arms 255 and 256 of the bracket 179. At

the other extremity the rock shaft 254 carries a rock arm 257 which provides a connection for the buttonholing mechanism with the needle jogging mechanism of the sewing machine so that during buttonhole formation the field of zigzag stitching of the sewing machine may be shifted from left to right at one end of a buttonhole and from right to left at the opposite end of the buttonhole. The mechanism which is operated by the rock arm 257 is not illustrated in the accompanying drawings nor will it be described herein because this mechanism may be of any known conventional form, for instance, as described in detail in the U.S. patent application Ser. No. 739,051 which has been referred to earlier in this specification. A coil spring 260 may be provided between the bracket 60 and the third arm 250 of the three-armed lever 209 to bias the cam follower pin 207 against the cam wall 206 of the cam member 200.

Referring to FIGS. 1, 9, and 10 the means will now be described by which the cam member 200 may be turned in quarter revolution increments during operation of the sewing machine to produce buttonhole-shaped tacks of stitches. Fast on the sewing machine main shaft 20 adjacent to the sprocket 24 is an eccentric 270 which is embraced by a strap 271 to which a sheet metal extension 272 is secured by a screw 273. Pivoted by a pin 274 to the extension 272 is a rock lever 275 which is journaled on the flanged bushing 72 which was previously described. Fulcrumed on a pin 276 secured in an upstanding arm 277 of the rock lever 275 is a pawl lever 278 formed with a ratchet engaging finger 279 and with a tail 280 to which a coil spring 281 is engaged. The coil spring may be anchored in the extremity of the lever arm 277 for biasing the pawl lever to urge the pawl finger 279 toward a ratchet wheel 282 which is formed as a part of the left-hand face of the cam member 200 as viewed in FIG. 10. As best shown in FIG. 9, the ratchet wheel 282 on the cam member 200 if formed with four substantially evenly spaced ratchet toothed portions 283. The ratchet toothed quadrants are separated alternately by blank portions 284 having a diameter substantially equal to that of the tips of the ratchet teeth and blank portions 285 formed at least partly with a recess 286 substantially equal to the root diameter of the ratchet teeth. Each of the blank portions 284 and 285 are of a width which exceeds the stroke of the pawl finger 279 in response to the drive impulses of the eccentric 270.

The left-hand face of the cam member 200, taken as viewed in FIG. 1, is preferably provided with a guard plate 290 to screen the face of the cam member 200 from the view of an operator of the sewing machine. The guard plate 290 is formed with an aperture 291, as shown in FIG. 9, substantially in register with an aperture 292 in the left side limb 51 of the frame 50. A spring member 293 secured to the frame 50 by a fastening screw 294 is formed with a bent finger 295 which extends through the apertures 291 and 292 and bears against the face of the ratchet wheel 282. The face of the ratchet wheel 282 is provided with depressions 296 arranged for cooperation with the spring finger 295 to provide a definite frictional resistance to turning movement of the cam member 200 in specific angular locations as the cam member 200 is turned throughout a revolution. It will be noticed in FIG. 9 that the depressions 296 are arranged substantially in four quadrants and that in every other quadrant there is provided a single depression 296 while in alternate quadrants a pair of depressions are provided. The first of each pair of depressions, when engaged by the finger 295 locates the cam member 200 in a position as shown in FIG. 9 with the pawl finger working in a recess 286 of a blank portion 285 on the ratchet wheel which position corresponds to a beginning or an end of a buttonhole. When the machine operator wishes to begin a buttonhole she manually turns the cam member to carry the spring finger 295 into the second of the pair of depressions 296 which will engage the pawl with the first ratchet tooth of succeeding toothed portion 283 and initiate the formation of one end of a buttonhole. The subsequent operation of the sewing machine will by way of the eccentric 270 cause the cam member 200 to move one-quarter turn during which time the cam surface 206

will shift the three-armed lever 209 gradually and during this shift will change the feed direction and shift the field of zigzag stitching from one side to the other thus producing one end of a round end buttonhole. The pawl finger 279 will then reach the succeeding blank portion 284 of the ratchet wheel, and the three-armed lever 209 will remain in fixed position while the sewing machine will continue to operate forming one side of the buttonhole for as long as the machine operator desires. When the pawl finger 279 reaches a plain blank portion 284 of the ratchet wheel 282, the spring finger 295 will be located adjacent to but not yet seated in a single depression 296, and the mechanism will rest in a position for formation of one side of a buttonhole. After one side of the buttonhole has been stitched to the extent deemed necessary by the operator, she simply nudges the cam member 200 until the spring finger 295 drops into the next adjacent single depression 296. This will shift the pawl finger into cooperation with the next toothed segment 283 and the ratchet device will again drive the cam member 200 to form the second end of the buttonhole and leave the controls set for sewing the second side of the buttonhole. The ratchet will drive the spring finger 295 into the first of the next pair of depressions which is the off or stored position of the device.

In the off or stored position, as illustrated in FIG. 9, the ratchet finger 279 being in a recess 286 will be urged to a lesser degree by the spring 281 and wear of the pawl finger will be minimized.

To set the machine for buttonholing, the operator, therefore, need only turn the cam member 90 to the position illustrated in the drawings in which the depending link 219 of the buttonholing mechanism linkages is in operative position in engagement with the shouldered pin 47 and also the operator should make a proper setting of the bight of zigzagging of the needle jogging mechanism of the sewing machine for buttonholing. Buttonholing can then be initiated simply by manually turning the cam member 200 for a sufficient distance as to bring the spring finger 295 into engagement with the next depression 296 as explained above.

Having thus set forth the nature of this invention, what is claimed herein is:

1. In a sewing machine having a work feeding mechanism including a means responsive to the angular position of a feed regulating shaft for varying the magnitude and direction of feed, a control device for said work feeding mechanism comprising, a first linkage operatively connected to a manually influenced adjusting means in said sewing machine, a second

linkage operatively connected to a pattern cam follower in said sewing machine, a third linkage operatively connected to a buttonholing unit in said sewing machine, an operator influenced selector element shiftably supported in said sewing machine, and means associated with said selector element for effecting operational engagement of any selected one of said linkages with said feed regulating shaft.

2. A control device for a sewing machine work feeding mechanism as set forth in claim 1 in which each of said linkages includes a separate manually adjustable means for balancing the forward and reverse directions of feed.

3. A control device for a sewing machine work feeding mechanism as set forth in claim 1 in which a bracket is secured to said feed regulating shaft and carries three separate connection elements, and in which said means associated with said selector element for effecting operational engagement of any selected one of said linkages with said feed regulating shaft includes cam means for shifting said linkages selectively into engagement each with a respective one of said connection elements on said bracket.

4. A control device for a sewing machine as set forth in claim 1 in which said manually influenced adjusting means for said first linkage is formed as a part of and shiftable with said operator influenced selector element.

5. In a sewing machine having a work feeding mechanism including a means responsive to the angular position of a feed regulating shaft for varying the magnitude and direction of feed, a control device for said work feeding mechanism comprising a supporting frame adapted to be secured in said sewing machine, three separate linkages carried by said frame, an axle journaled in said frame, a manually rotatable cam disk journaled on said axle, three separate cam means formed in said cam disk, follower means on each of said three separate linkages each tracking a respective one of said three separate

35 cam means for shifting said linkages selectively into operative engagement with said feed regulating shaft, said cam means tracked by a first of said separate linkages providing for manual influence of magnitude and direction of feed while said first linkage is positioned in operative engagement with said feed regulating shaft, a second of said separate linkages including pattern cam follower means for sewing decorative stitches with repetitive work feed variations, an intermittently driven buttonholing control unit journaled on said axle, and means on a third of said separate linkages responsive to said buttonholing control unit for influencing regulation of said work feeding mechanism.
